UNITED STATES PATENT OFFICE.

ROBERT S. HISLOP, OF RACINE, WISCONSIN, ASSIGNOR TO RACINE CONFECTIONERS MACHINERY COMPANY, OF RACINE, WISCONSIN, A CORPORATION OF WISCONSIN.

CANDY-MAKING MACHINE.

Application filed June 5, 1922. Serial No. 565,916.

To all whom it may concern:

Be it known that I, ROBERT S. HISLOP, a citizen of the United States, residing at Racine, county of Racine, State of Wisconsin, have invented a certain new and useful Improvement in Candy-Making Machines, of which the following is a specification, reference being had therein to the accompanying drawings.

10 This invention relates to machines for the manufacture of candy, such as chocolates or the like, or of small cookies, cakes, or similar articles which can be formed from semi-liquid or plastic material and hardened by cooling, drying, or baking. Although applicable to machines of other types, the invention is herein shown as applied to and embodied in a chocolate dropping machine of the character shown in 15 Letters Patent No. 791,611, granted June 6, 1905, to Joseph M. Demerath and a further development of which is described in the application for Letters Patent filed November 15, 1920, by Willis N. Hartshorn, 20 Serial No. 424,013.

The present invention has for its object to provide means whereby cakes or confections having an ornamental form and appearance may be conveniently, rapidly and 30 economically produced, without the use of molds, by mechanism operating upon the dropping or depositing principle.

To this end the invention, in its preferred form, comprises a nozzle or equivalent device adapted to deposit measured quantities of the plastic material upon a receiver or carrier having a flat surface, said nozzle having an orifice which, as a whole, is preferably of non-circular but 35 symmetrical form, means being provided for oscillating or turning said nozzle on its axis at a predetermined time during the depositing operation, whereby the confection produced will have a more or less twisted or spiral form. The mechanism also 45 operates in proper time relation with the up and down movement of a table on which the goods are deposited, this movement being desirable to taper off the top of the 50 piece of goods which is being produced.

The foregoing object of the invention, together with means whereby the same may be carried into effect, will best be under-

stood from the following description of one form or embodiment thereof illustrated in 55 the accompanying drawings, in which:

Fig. 1 is a side elevation, partly broken away, of so much of the machine as is necessary to an understanding of the invention.

Fig. 2 is an elevation, partly in section 60 on the line 2—2, Fig. 1, of one end of the upper portion of the machine shown in the latter figure.

Fig. 3 is a section taken substantially on the line 3—3, Fig. 2. 65

Fig. 4 is a horizontal section taken substantially on the line 4, Fig. 3.

Figs. 5, 6, 7 and 8, and 9, 10, 11 and 12 are detail views in plan and elevation respectively of several forms of confections 70 capable of being made by the machine.

Figs. 13, 14, 15 and 16 are bottom plan views respectively of the nozzles by which these confections are formed.

As in the patent and prior application 75 above preferred to, the machine frame 15 is arranged to support a hopper or reservoir 16 adapted to contain a quantity of plastic or semi-liquid material, such as a melted chocolate compound. At its bottom, the reservoir or hopper 16 communicates with a transverse series of nozzles 17, said communication being controlled by a combined measuring and ejecting valve device 18 which may be substantially as shown and de- 80

scribed in said Demerath patent. The valve device 18 is enclosed by a casing 26 at the bottom of the hopper 16 and has a port communicating therewith, said casing and hopper being preferably formed with hollow 90 jackets for the circulation of a heating fluid. Below the hopper 16 and nozzle 17 is a carrier or receiver 14 for the material deposited by said nozzles. Said carrier being moved intermittently, between the depositing operations, to receive fresh deposits from the nozzles 17, by means of a chain or chains 19 passing over sprockets 20 at the ends of the machine and actuated by suitable intermittent feeding mechanism. Said carrier 95 may be as indicated in the drawings in the form of a continuous flexible sheet metal belt having a polished surface, as described in the Hartshorn application above referred to, or it may comprise a series of trays one 100

105 piece of which is shown in dot and dash lines at

32, as in said Demerath patent, said trays, however, in such event, having flat polished surfaces similar to the surface of the belt in the Hartshorn application instead of being provided with mold cavities as in the Demerath patent. Mechanism is also provided whereby the carrier is lowered after the deposit has been partially made but before the nozzles have completed their 10 turning movement. This is essential in order that the material may be drawn up in the shape of a cone in which the twist is brought to a point to form the apex. This mechanism may be substantially as 15 disclosed in the Hartshorn application, but is shown in connection with the present application and will be hereinafter more fully described.

Journalled in the frame 15, and extending 20 transversely thereof, is a power shaft 5, said shaft receiving power in any suitable manner, as through a belt pulley 6. Fast upon the shaft 5 is a pinion 7 which meshes with a gear 8 secured to the outer end of a 25 shaft 9 projecting through the frame. The gear 8 meshes with a second gear 10 fast upon a transverse shaft 13 journalled in the frame 15. The gear 10 carries an adjustable crank pin 11 to which is connected a pitman 30 12 for operating the above mentioned feeding mechanism for the chains 19. Fast on the shaft 9 at each side of the machine are located eccentrics 70 only one of which is shown in the drawings (see Fig. 1). On 35 these eccentrics rests a member 71 which is secured to the under side of a table 72 across which the carrier 14 travels. One end of the table 72 is pivoted as indicated at 73, the other end being free to move up in close 40 proximity to the nozzles when actuated by the eccentrics, and move down away from the nozzles when the eccentrics so permit.

The mechanism for operating the valve device 18 is, in the machine illustrated in the 45 drawings, located at the side of the machine opposite that shown in Figure 1, and is actuated by suitable connections with the shaft 13. This mechanism, and the feeding mechanism for the chains 19, are not shown herein, as specifically they form no portion of the 50 present invention and may be as fully disclosed in said patent to Demerath.

In accordance with the present invention, the nozzles 17 are journalled in a plate 21 55 carried by the bottom of the valve casing 23, said nozzles having at their upper edges flanges or collars 22 which are received in countersunk openings in the upper face of said plate. Secured to each of the nozzles 17 below the plate 21 is a pinion 23, the several pinions of the series being engaged by a rack formed on a bar 24 which is guided for longitudinal movement on the bottom of the plate 21. In order that the plate 21 may 60 be readily removed for the purpose of chang-

ing the nozzles 17, when confections of a different form are to be made, said plate is detachably secured to the bottom of the valve casing 23. To this end, in the construction shown, one edge of the plate 21 is formed 70 with notches 50 to receive screws 51 entering the bottom of the valve casing, while at its opposite edge said plate is formed with a hooked flange 52 which engages a shoulder 53 on the valve casing, said flange being secured to the side of said casing by means of threaded studs 27 projecting from said casing through slots 29 in said flange and provided at their outer ends with wing nuts 28. The rack bar 24 is supported and guided on 75 the bottom of the plate 21 by means of several angular brackets 25, each having a lower horizontal flange disposed beneath said rack bar and a vertical flange which is secured to the outer face of the flange 52 by means of 80 screws.

The rack 24 is longitudinally reciprocated, to oscillate the pinions 23 and nozzles 17, by means of the following mechanism. Secured to the under side of the rack bar 24, as by 85 means of screws 30, is a bracket 31. Carried by the bracket 31 is a stud 3 which is engaged by the forked lower end of an arm 33 fast upon a rock shaft 34 which is journalled in a bracket 35 secured to the hopper or reservoir 16. The rock shaft 34 is operatively connected, through bevel gears 36, with a second rock shaft 37 journalled in the bracket 35 and in a second bracket 4 also secured to the hopper or reservoir 16. Fast 90 upon the end of the rock shaft 37 is an arm 38 formed with a longitudinal series of openings 39 each adapted to receive a pin 40 by means of which may be variably connected to said arm the upper end of an eccentric rod 41. The rod 41 is secured at its lower end to an eccentric strap 42 embracing an eccentric 43 having a hub 74 which is adjustably secured to the shaft 9 by means of a set screw 44. 100

From the foregoing it will be seen that by changing the connection of the rod 41 with the arm 38, the amplitude of oscillation by the nozzles 17 may be adjusted while by angularly adjusting the eccentric 43 on the 105 shaft 9 the point in the cycle of operations at which such oscillation takes place may be varied.

In the form of the invention shown in Figures 3 and 14, each of the nozzles 17 is 110 provided with a central discharge orifice 45 having at its outlet end radial extensions 46, said extensions being individually eccentric to the axis of the nozzle but being collectively symmetrical with respect thereto. 115 The confection produced by a nozzle of this form is shown in Figures 6 and 10. The material discharged through the central orifice 45 forms the body 47 of the confection, while the material from the extensions 46 will 120 125 130 135 140

form protuberances 48 at the edges thereof. As the nozzle is turned, the material of the protuberances 48 will be twisted into a spiral form. The semi-fluid condition of the material causes the mass deposited to spread upon the surface of the carrier 14, and toward the end of the operation, after the greater portion of the mass has been ejected through the nozzles, the carrier 14 is lowered, increasing the distance between it and the orifices of the nozzles, and thereby causing the material to be drawn up and tapered in conical shape, as shown in Figure 10. The viscosity of the material at this time causes the portion thereof last to leave the nozzle to be drawn into a stream or thread of decreasing diameter, so that the material of the protuberances 48 is drawn inwardly over the top of the body 47 to form spiral ribs 49 which meet substantially in the center of the top of the confection.

The nozzle 170 shown in Figure 13 is substantially similar to the nozzle 17 shown in Figure 10, the central orifice 45 thereof being, however, formed with a greater number of radial extensions 460 each of which is of less width than the extensions 46 of the nozzle 17, so that the body 470 of the confection shown in Figures 5 and 9 is provided around its periphery with a considerable number of thin radial protuberances 480 from which extend, over the top of the body 470, a corresponding number of spiral ribs 490 meeting at the top of the body in the center.

The nozzle 171 shown in Figure 15 is provided with a series of eccentric supplementary orifices 461, being connected by comparatively narrow slots 462. The body 471 of the confection formed by this nozzle, as shown in Figures 7 and 11, is surrounded by a series of more or less distinct bodies 481 which, however, by reason of the spreading of the material, are more or less merged with the main body 471, said supplementary bodies 481 being connected at the top of the main body 471 by spiral ribs 491.

In the nozzle 172 shown in Figure 16, the central discharge orifice is omitted, and the nozzle is provided with a plurality of eccentric orifices 463 symmetrically arranged about the center of the nozzle. As shown in Figures 8 and 12, the material deposited by the orifices 463 will form a corresponding number of separate bodies 482, which, due to the spreading of material, will be more or less merged with one another, and each of which is provided with an extension 492 which is drawn out into spiral form over the next adjacent body and toward the center of the confection as a whole.

The above-described specific forms which the nozzles may assume, and the shapes of the confections formed thereby, are merely illustrative of the invention, and it will be obvious that the form of the nozzle may be

varied almost without limit, and that the shapes of the confections will be correspondingly varied.

The amount of twist given to the spiral ribs 49, 490, etc., will be controlled by the amplitude of oscillation of the nozzles 17, this being, in turn, determined by the point of connection of the rod 41 with the arm 38. The time with respect to the time of operation of the valve device 18, at which the twisting takes place, as controlled by the adjustment of the eccentric 43, will determine to a considerable extent the shape of the protuberances or bodies 48, 480, etc., with respect to the ribs 49, 490, etc. Thus, by comparison of Figures 6 and 7, it will be seen that in the formation of the confection shown in Figure 7, the turning movement of the nozzle commenced earlier in the depositing operation than in the case of the confection shown in Figure 6, so that the bodies 481 have been, to a certain extent, elongated circumferentially of the body 471 prior to the formation of the ribs 491, whereas in the formation of the confection shown in Figure 6, the bodies 48 are not elongated circumferentially, the twist being substantially confined to the ribs 49. In the confection shown in Figure 5, the twist is also substantially confined to the ribs, the projections 480 being merged almost immediately into the ribs 490. From the foregoing it will be seen that the shapes produced by the machine may be varied, not only by changing the nozzles, but by different adjustments of the mechanism with the same nozzle.

What I claim is:—

1. In a machine of the character described, the combination with a depositor for plastic material, and a receiver for the material deposited, of means for relatively turning said depositor and receiver to twist said material as it is deposited, said means having provision for varying the extent of such turning movement.

2. In a machine of the character described, in combination, a container for plastic material, a nozzle communicating therewith, and means for turning said nozzle upon its axis as said material is discharged therethrough, said means having provision for varying the extent of such turning movement.

3. In a machine of the character described, the combination with a depositor for plastic material, means for controlling the discharge of material therefrom, and a receiver for the material deposited, of means for relatively turning said depositor and receiver to twist said material as it is deposited, said turning means being adjustable to vary the time of such turning movement with respect to the deposit of said material.

4. In a machine of the character described, the combination with a depositor for plastic

- material, means for controlling the discharge of material therefrom, and a receiver for the material deposited, of means for relatively turning said depositor and receiver to twist said material as it is deposited, said turning means having provision for varying the extent of such turning movement and being adjustable to vary the time thereof.
5. In a machine of the character described, in combination, a container for plastic material, a nozzle communicating therewith, means for controlling the discharge of material through said nozzle, and means for turning said nozzle upon its axis as said material is discharged therethrough, said means being adjustable to vary the time of such turning movement with respect to the discharge of said material.
6. In a machine of the character described, in combination, a container for plastic material, a nozzle communicating therewith, means for controlling the discharge of material through said nozzle, and means for turning said nozzle upon its axis as said material is discharged therethrough, said means having provision for varying the extent of such turning movement and being adjustable to vary the time thereof with respect to the discharge of said material.
7. In a machine of the character described, in combination, a container for plastic ma-
- terial, a valve casing below said container and communicating therewith, a valve device in said casing, a plate having at one edge a notch and at the opposite edge a hooked flange also provided with a notch, said casing having a shoulder engaged by said hooked flange, fastening devices engaging said notches for detachably securing 40 said plate to said casing, a nozzle rotatably mounted in said plate and communicating with said casing, and means for oscillating said nozzle.
8. In a machine of the character described, in combination, a container for plastic material, a valve casing below said container and communicating therewith, a valve device in said casing, a plate having a hooked flange provided with notches, said casing 50 having a shoulder engaged by said hooked flange, fastening devices engaging said notches for detachably securing said flange to said casing, a nozzle rotatably mounted in said plate and communicating with said casing, a pinion carried by said nozzle, a rack bar cooperating with said pinion, guides having a flange for supporting said rack bar and a second flange engaging the flange on said plate, and means for reciprocating said rack bar.

In testimony whereof I affix my signature.

ROBERT S. HISLOP.
